(57) **CLAIM**

The ornamental design for a seat extender for vehicle as shown and described.

DESCRIPTION

FIG. 1 is a top, front, right side perspective view of a seat extender for vehicle of the present invention.

FIG. 2 is a top view thereof;

FIG. 3 is a bottom view thereof;

FIG. 4 is a front view thereof;

FIG. 5 is a back view thereof;

FIG. 6 is a left side view thereof;

FIG. 7 is a right side view thereof; and,

FIG. 8 is top, front, right side perspective view thereof, showing the seat extender for vehicle in a condition of use. The dash-dash broken lines shown in FIGS. 1-7 illustrate portions of the seat extender for vehicle which form no part of the claimed design. The dash-dash broken lines depicting portions of a vehicle shown in FIG. 8 show environmental structure which forms no part of the claimed design. The dash-dash broken lines shown in FIG. 8 depicting a seat extender show environmental structure which forms no part of the claimed design.
